PITCHER OR SIMILAR ARTICLE

Charles O. Bliss, Hollywood, Calif.

Application February 3, 1950, Serial No. 7,712

Term of patent 14 years

(Cl. D44—21)

To all whom it may concern:

Be it known that I, Charles O. Bliss, a citizen of the United States, residing at Hollywood, in the county of Los Angeles, in the State of California, have invented a new, original, and ornamental Design for Pitcher or Similar Article, of which the following is a specification, reference being had to the accompanying drawings, forming a part hereof, and wherein:

Fig. 1 is a side elevational view of a pitcher or similar article showing my new design;

Figs. 2 and 3 are respectively rear and front elevational views; and

Figs. 4 and 5 are respectively bottom plan and top plan views thereof.

The drawing is shaded to indicate that the upper section of the article is transparent, while the lower section is opaque.

I claim:

The ornamental design for a pitcher or similar article, as shown and described.

CHARLES O. BLISS.
